UNITED STATES PATENT OFFICE.

WILLIAM F. HALL, OF BOSTON, MASSACHUSETTS.

DOOR-KNOB ATTACHMENT.

SPECIFICATION forming part of Letters Patent No. 278,704, dated June 5, 1883.

Application filed April 9, 1883. (No model.)

To all whom it may concern:

Be it known that I, WILLIAM F. HALL, a citizen of the United States, residing at Boston, in the county of Suffolk and State of Massachusetts, have invented an Improvement in Door-Knobs, of which the following is a full, clear, and exact description, reference being had to the accompanying drawings, making part of this specification, in which—

10 Figure 1 is a longitudinal section through a pair of door-knobs attached to their spindle, and constructed in accordance with my invention. Fig. 2 is a section through one of the door-knobs detached.

15 My invention has for its object to facilitate the method of attaching door-knobs to their spindles; and the novelty consists in the construction and arrangement of parts, as will be hereinafter more fully set forth and specifically 20 claimed.

In the drawings, A B represent the knobs, which are secured to the spindle *a* by means of screws passing through the necks or shanks *b* of the knobs.

25 C C are two rose-plates, which are screwed to opposite sides of the door, and are each provided with a neck, *c*, which fits over the neck *b* of the knobs.

The knob B is provided on its inner side

with an annular recess, *d*, formed by milling 30 or otherwise, for the purpose of receiving one or more washers, *e*, which are thus interposed between the end of the neck *c* of the rose C and the knob B. By thus constructing the knob B with an annular recess for the reception of the washers *e*, the knobs A B can be 35 nicely adjusted to fit doors of varying thickness, and all rattle and play thus avoided. Furthermore, a great saving in time and labor is effected, as the holes in the spindle *a* for the 40 reception of the screws which hold the knobs in place will not have to be so accurately bored as heretofore, thus lessening the expense of manufacture.

What I claim as my invention, and desire to 45 secure by Letters Patent, is—

A door-knob provided with an annular recess, *d*, and neck *b*, in combination with a rose, C, with its neck *c*, and the washers *e*, all constructed to operate substantially in the man- 50 ner and for the purpose set forth.

Witness my hand this 7th day of April, A. D. 1883.

WILLIAM F. HALL.

In presence of—

CLARA P. HALL,
HENRY Y. HALL.
